ALBERT E. TOLIN, OF ANDERSON, INDIANA, ASSIGNOR, BY MESNE ASSIGNMENTS, TO
WILLIAM J. WOOLLEY, OF ANDERSON, INDIANA.

BUTTON-FEEDING MECHANISM FOR BUTTON-ATTACHING MACHINES.

1,239,846.

Specification of Letters Patent. Patented Sept. 11, 1917.

Application filed November 30, 1914. Serial No. 374,723.

To all whom it may concern:

Be it known that I, ALBERT E. TOLIN, a citizen of the United States, residing at Anderson, in the county of Madison and 5 State of Indiana, have invented a new and useful Button-Feeding Mechanism for Button-Attaching Machines, of which the following is a specification, reference being had to the accompanying drawings and to 10 the letters and figures of reference marked thereon.

This invention relates to the type of button-attaching machine that includes apparatus for forming the fastening devices required for attaching buttons to shoes or other articles, the invention having reference more particularly to a machine of the above mentioned character that is adapted to be used not only in factories for permanently attaching buttons to articles, but in 15 retail shoe stores for attaching buttons to shoes to suit the purchaser; or for re-setting buttons that may have been temporarily attached to shoes in factories.

20 An object of the invention is to provide an improved button-attaching machine that shall be so constructed as to be adapted for rapid operation, more particularly by foot power, so that the hands of the operator are free to be used for handling and 25 controlling the articles to which the buttons are to be applied; an aim being to provide a button-attaching machine of simple and compact form that may be constructed 30 at relatively small cost and sold at a price that would warrant their purchase and use generally, and more particularly by the smaller retail shoe dealers.

Another object is to provide an improved 35 button-attaching machine that shall be capable of holding and controlling a variety of buttons, such as those of different sizes or different colors, either of which may be quickly selected for use; which machine 40 shall be so constructed as to permit the ready removal of one or more of the varieties of buttons to be replaced by one or more other varieties if desired, and without entailing the disadvantages inseparable 45 from the caretaking and handling of separate magazines or button-holding devices hitherto forming part of the equipment of button-attaching machines used to some extent.

50 A further object is to provide improved

button-controlling and feeding apparatus that shall be so constructed as to operate yieldingly and smoothly, and yet reliably and without harsh treatment or injurious effects on the buttons which are liable to 60 be marred on their surfaces to the extent of being unsightly in appearance.

With the above-mentioned and other objects in view, the invention consists in a machine having various novel features 65 whereby the above-mentioned and other objects are practically realized; the invention 70 contemplating various modifications of a preferred construction, and also including the novel parts and combinations and arrangements of parts as hereinafter particularly described and further defined in the accompanying claims.

Referring to the drawings,—Figure 1 is a side elevation of a button-attaching machine constructed substantially in accordance with the invention; Fig. 2 is a top plan of the machine; Fig. 3 is a fragmentary section on the line A A on Fig. 1; Fig. 4 is a fragmentary side elevation of portions of Fig. 1 on an enlarged scale; Fig. 5 is a front elevation of the main part of the machine; Fig. 6 is a vertical central section of the main part of the machine; Fig. 7 is a fragmentary front elevation omitting parts in order to expose other parts to view; Fig. 8 is a perspective view of detached parts of the machine; Fig. 9 is a fragmentary front elevation of the machine partially in section; Fig. 10 is a perspective view of an improved button guide; Fig. 11 is a perspective view of novel parts of the machine for assisting in the delivery of the buttons; Fig. 12 is a perspective view of a housing shutter preferably employed; Fig. 13 is a fragmentary vertical sectional elevation; Fig. 14 is a perspective view of the button elevators of the machine; Fig. 15 is a fragmentary top plan of the button magazine; Fig. 16 is a fragmentary section of the button chute and device for stopping and holding the buttons on the chute; Fig. 17 is a side elevation of a cam plate forming a part of the machine; Fig. 18 is a fragmentary section on the plane of the line F F on Fig. 15; Fig. 19 is a fragmentary section approximately on the line G G on Fig. 13; and, Fig. 20 is a section approximately on the line H H on Fig. 4.

ent figures of the drawings indicate like parts or elements hereinafter particularly referred to.

A button-attaching machine, by which the objects of the invention are practically attained, preferably is so constructed as to permit of convenient operation thereof by an operator in standing position, and to this end the machine comprises a suitable base 1 provided with supporting legs 2, 3, 4, and also a fulcrum arm 5 provided with a pivot 6 to which a foot lever 7 is connected, the arm 5 being on the rear of the base and the foot lever extending under the base 10 through the forward leg 2. A hollow pillar 8 is fixedly supported upon the base 1 and it has a spring 9 connected thereto, the spring being connected also to the forward portion of the foot lever for drawing the latter upward and normally holding it in elevated position. An improved housing for supporting the principal mechanism is provided and comprises a bottom 10 which is fixedly secured to the top of the pillar 8 and has a table 11 on the rear portion thereof, the table being suitable for supporting hand-tools or various articles and it has a suitable number of depressions or open compartments 12, 13, 14, 15, 16 in which small supplies of different kinds or styles of buttons may be placed so as to be conveniently accessible. The housing includes also an upright front wall 17, side walls 18 and 19 connected to the front wall, and a rear wall 20 connected to the side walls, all the walls being secured upon the bottom 10. The front of the front wall 17 has a rigid head-block 21 thereon for supporting and guiding different parts of the machine. The top portion of the front wall has a forwardly extending projection 22 thereon, the wall having also an opening or slot 23 in its upper portion. The rear wall 20 has an inclined upper portion 24 extending forwardly and to a higher plane than the front wall, so that the top of the housing is inclined. The inclined portion 24 of the rear wall has a projecting rib 25 on the middle of its rear side. The side walls 18 and 19 have lateral projections 26, that are on the plane of the inclined portion 24 of the rear wall. The housing is provided with a top or roof plate 28 which is inclined forwardly and forms a chute for the buttons. The top plate 28 supports an open magazine frame which comprises two rearwardly extending side-bars 29 and 30 adapted to constitute portions of chutes and a cross-bar 31 connected to the ends of the side-bars. A magazine for the buttons comprises two inclined sides 32 and 33 connected to the projections 26 and to the side bars 29 and 30, respectively, the wall portion 24 forming the front of the magazine which has a back wall 34 connected to the side walls 32 and 33 and

also to the cross-bar 31. The side walls 32 and 33 have bottom portions 35 and 36 formed thereon respectively that extend each toward the other, there being suitable space between the bottom portions. A partitional wall 37 preferably is provided and is secured to the back wall 34 and extends from the plane of the portions upward above the plane of the magazine frame and into the rib 25 and to a tongue 38 extending from the roof plate rearward upon the rib. The wall has a forwardly extending projection 39 standing upon the tongue 38 for assisting to guide the buttons on the chute. The magazine preferably being divided into two compartments for different kinds of buttons, two elevators 40 and 41 consequently are provided which are arranged on opposite sides respectively of the partitional wall 37 and secured at the lower ends to a foot-bar 42 which is slightly thicker than the partitional wall and is arranged below the wall. The tops of the elevators are inclined to correspond to the inclination of the magazine frame which preferably is slightly less than the inclination of the top or roof plate 28. The top of the elevator 40 has a channel or groove 43 therein, the other elevator 41 having a similar channel 44 in its top for guiding the eyes or shanks of buttons which may be elevated from the magazine chambers to the chute on the tops of the elevators. The chute has two guide channels 45 and 46 in the top thereof that extend from the end of the tongue 38 and downward in the top of the roof plate 28 to the lower end thereof. The side bars 29 and 30 are adapted for supporting and guiding buttons, one having a guide channel 47 in the top thereof that is connected with a channel 48 formed in the top of the plate 28 and extending convergently to the lower end of the channel 45, the other side bar 30 having a similar channel 49 that is connected with a channel 50 formed also in the top of the plate 28 and extending convergently to the lower end of the channel 46 for guiding the eyes or shanks of the buttons that may be placed upon the magazine frame. A controlling rod 51 is secured to the lower ends of the elevators and has a stop collar 52 thereon to be moved into contact with a spring 53 supported upon the table 11 through which the rod 51 extends, the lower portion of the rod being provided with a nut 54 or similar stop device that is in contact with the bottom of the table when the rod is in elevated position. The bottoms of the elevators preferably are provided with a spring 55 to be engaged by a device for lifting the elevators. For the purpose of actuating and controlling various parts of the machine a suitable cam plate or bar 56 is provided which is arranged adjacent to the

inner side of the side wall 18 and suitably guided for vertical movement, the upper portion of the plate having an arm 57 thereon that extends over to the opposite wall 19 and has a downwardly extending finger 58 thereon. The cam plate or bar is operated and controlled directly by means of a connecting rod 59 which is suitably connected thereto and extends through the pillar 8 and is connected to the foot lever 7, the cam plate or bar being normally held in elevated position by means of the spring 9. The side wall 18 has a suitable opening that is normally closed by a removable section or plate 60 which supports a guide pin 61 on its inner side to be engaged by a dog 62 which is mounted on a pivot 63 secured to the plate or bar 56 for forcing the dog into engagement with ratchet teeth 64 formed on the inner side of the rear wall 20 of the housing. A plate spring 65 is mounted also on the plate or bar 56 and engages the dog, the latter being adapted to be held by the spring either in contact with or away from the ratchet teeth; and the dog is pushed away from the ratchet teeth by means of a guide pin 66 supported by the side wall 18, the action taking place when the plate or bar 56 descends. The dog is adapted to stop the cam plate 56 when moved upward to the required point.

Two pivot bolts or shafts 67 and 68 are supported by the side walls 18 and 19, the bolt 67 having a journal bearing 69 thereon which constitutes a nut that is screwed onto the bolt and against the outer side of the wall 18 so as to rigidly secure the bolt and the bearing to the wall, the outer end of the bearing having a guide collar 70 thereon.

A lever is pivoted between its ends on the bearing 69 so as to constitute an arm 71 that extends rearward and upward and is provided with a wrist pin 72, and an arm 73 that extends forward beyond the front of the side wall. The arm 71 has a laterally extending finger 74 thereon that normally engages the spring 55 for holding the elevators in their elevated position. The wrist pin 72 extends into and through a suitable aperture in the side wall 18 of the housing and between two engagement portions 75 and 76 formed in an opening in the plate or bar 56 which permits a limited extent of movement of the plate or bar while the lever remains at rest, the lever being moved on further movement of the plate 56. The head-block 21 is provided with a stop projection 77 whereby the lever is stopped by the arm 73 coming into contact with the projection.

Simple mechanism is shown for forming wire staples and driving them for attaching buttons to articles in a convenient manner, the mechanism comprising a main bar 78 mounted in the head-block 21 and having

a longitudinal guideway therein. The upper portion of the bar is provided with a transverse wrist-pin 83 whereby to operate and control the bar. The lower end of the bar is adapted to shear off a section of wire 70 to form a staple when the wire is fed on downward movement of the bar. A ram or secondary bar 86 is provided which is fitted into and longitudinally guided in the guideway of the main bar. The upper portion 75 of the ram is provided with a lateral wrist-pin 89 whereby to operate and control the ram. The mechanism includes also an arbor bar 90 that is suitably mounted in the head-block 21 at right angles to the main bar 78 and so as to be movable longitudinally, the outer end or forward portion being formed as an arbor 91 on which to form the loop of a staple. The arbor bar is provided with a wrist pin 94 for operation and control of the arbor. A bell crank is supported to rock on the pivot bolt 67 and has one arm 95 suitably connected with the wrist pin 83, the arm extending through the aperture 23 in the front wall of the housing, 80 the remaining arm 96 of the bell crank extending downward and having a wrist-pin 97 on its lower portion. A relatively larger bell crank is supported to rock on the pivot bolt 68 and has one arm 98 extending 85 through the aperture 23 above the arm 95 and suitably connected with the wrist-pin 89, the remaining arm 99 of the bell crank extending downward and having a wrist-pin 100 thereon. The inner portion of the 100 arbor bar 90 and also the arms 96 and 99 are arranged on one side of the cam plate or bar 56, so that they may be operated synchronically by the plate or bar which is suitably provided with cams, the latter being 105 suitably formed as slots or channels in the plate or bar 56 which has one channel receiving the wrist-pin 94 and comprising an inclined cam portion 101, from the lower end of which extends a vertical portion 102 110 that is adjacent to the front wall 17, a vertical portion 103 extending from the upper end of the cam portion 101 farther away from the front wall so that the arbor bar is projected when the cam plate is elevated 115 and is retracted when the plate is lowered. The cam plate has also another channel that receives the wrist-pin 97 and comprises an upwardly and rearwardly extending cam portion 104 from the lower end of which a 120 vertical portion 105 extends, a vertical portion 106 extending upward from the upper end of the cam portion, another cam portion 107 extending upward and rearward from the upper end of the vertical portion 125 106, the channel therefore having two cam portions and a vertical portion 108 extending from the upper end of the cam portion 107. The vertical portions permit movement of the cam plate without moving the 130

wrist-pin, the latter being moved by the cam portions. When the wrist-pin is in the vertical portion 105, the cam plate being elevated, the main bar 78 is held in elevated position and is moved downward when the cam plate is drawn downward so that the wrist-pin is carried over to the vertical portion 108. The cam plate 56 has still another channel which receives the 10 wrist-pin 100 and comprises an upwardly and rearwardly extending cam portion 109, from the lower end of which a vertical portion 110 extends; a vertical portion 111 extending from the upper end of the cam portion, and another cam portion 112 extends upward and rearward from the upper end of the vertical portion 111, another vertical portion 113 extending from the upper end of the cam portion 112. The upper 20 end of the vertical portion 113 preferably is sufficiently broad to permit slight swinging movement of the arm 99, the upper end of the vertical portion 108 having a recess 114 to receive the wrist-pin 97 so as to permit slight swinging movement of the arm 96, in order to permit the bar 78 and the ram 86 to be thrust downward onto the work and compensate for variations in thickness of articles worked upon and thus 30 avoid straining of the mechanism. The front wall 17 of the housing has also a projecting abutment arm 115 which supports an anvil or clenching die 116, in the top of which are two adjacently arranged recesses 35 117 and 118 having curved bottoms for causing the ends of the staple legs to be turned over and clenched on the under side of the article to which the buttons may be attached. A curved guide bar 119 is provided 40 and its upper end is secured to the projection 22 of the front wall of the housing to form a continuation of the top or roof plate 28 and therewith form an inclined chute for the buttons. The lower end of the 45 guide bar is provided with a supporting base 120 that is secured to the head-block 21 and conveniently performs the function of a cap plate for the bearings that guide the main bar 78, the lower end of the base 50 having an opening 121 therein in which the front face of the guide bar terminates. The upper portion of the guide bar has a channel section 122 that forms a continuation of the channel 48, and also a channel section 55 123 that forms a continuation of the channel 50, the channel sections having connection respectively with the channels 45 and 46, being convergent each to the other and connected with a guide channel 124 formed 60 in the bar and extending down to the lower end of the guide bar, the lower end of the channel being arranged so as to guide the eye or shank of the button into the slot 87 of the ram.

65 A plate 125 is provided and fixedly se-

cured to the chute or plate 28 so as to be spaced slightly away from the latter to serve as a frame member and also a guide plate permitting the buttons to slide down the chute under the guide plate with the 70 eyes or shanks of the buttons in the guide channels, the guide plate preventing accidental disarrangement or scrambling of the buttons. The plate 125 has a suitable lid frame 126 thereon that extends above the 75 magazine frame and serves as a guide plate above the channels 47 and 49 without, however, covering the upper or inlet ends of the channels, and a magazine cover 127 is hinged to and normally rests upon the frame 80 126. The plate 125 has a guide projection thereon that extends into the frame above the tongue 38 and to the guide projection 39, and is shaped to form two inclined guides 128 and 129 that extend divergently 85 from the end of the guide 39 for the purpose of deflecting buttons from the tongue 38 over onto the inclined back wall portion 24 that forms an inclined front wall of the magazine, such action being desired in case 90 the buttons are devoid of eyes or shanks, or in case the shanks do not happen to be brought fairly into the guide channels 45 and 46. The member 125 supports suitable stop devices adapted to operate above the 95 lower end portions of the guide channels 45, 46, 48 and 50 for holding the buttons in the channels ready to be selected for use, the member 125 having a suitable number of 100 apertures 130 therein through which the devices operate, one for each channel. In the preferable form of construction of the stop devices a pivot rod 131 is suitably supported by the member 125 so as to extend across the apertures, and it supports a suitable number of tumbling devices comprising 105 each a finger 132 or 132' that extends through an aperture toward the adjacent guide channel so as to arrest the movement of the buttons down the channel, and an 110 arm 133 or 133' extending into contact with the top of the member 125 beyond the aperture. When the arm is swung over so as to extend downward upon the member 125 the finger is swung upward out of the aperture 115 and releases the buttons. When the buttons are released in one of the channels, they slide downward onto the guide 119 and are temporarily retained by a movable gate that is connected to a hinge rod 134 supported upon 120 the member 125, the gate comprising a base plate 135 extending from the hinge rod downward upon the top of the member 125. A base plate 136 is connected also to the hinge rod 134 and suitably adapted to co-operate with the gate. The base plate 135 of the gate is engaged by a suitable spring 137 for yieldingly holding the gate down to normal position. The plate 135 has an aperture 138 therein and a gate portion 139 that 125

130

extends downward over the end of the member 125 approximately to the guide bar 119 and has a slot 140 therein extending from the aperture, the gate portion 139 being 5 adapted to arrest the movement of the buttons. The plate 136 has a curved guide 141 on its end that is supported on a higher plane than the gate plate and extends downward adjacent to the gate and toward the 10 guide bar 119, the guide being supported by its outer edge so that an object sliding up the guide may drop off from the upper or rear end thereof onto an inclined guide 142 which is supported by the gate plate 15 135 and extends forward and downward under the guide 141 and toward the plate 135.

For the purpose of moving or transferring the buttons from the gate 139 to the lower 20 portion of the ram 86 the arm 73 of the rocking lever is provided on one side with a boss 143 having a pivot pin 144 that extends horizontally opposite the front of the guide bar 119. The pivot pin carries an open head 25 formed of two plates 145 and 146 that are pivotally connected to the pivot pin 144, the plates being spaced apart and having a guide pin 147 secured thereto below the pivot pin, the plates being secured to a cross-bar 148 30 arranged forward of the plane of the pivot pin and the guide pin. A finger bar 149 that is approximately S-shaped is arranged in the open head, being between the two plates thereof, so that the upper end of the 35 bar extends away from the guide bar 119 and over above the cross-bar 148, the lower portion of the finger bar extending toward the guide bar 119. The finger bar has a vertical slot 150 which receives the pivot pin 40 144, and a slot 151 which receives the guide pin 147, so that the finger bar is vertically movable in the head and may swing with the head on the pivot pin. A spring 152 co-operates with the boss 143 and the open 45 head to swing the lower end of the finger bar toward the guide bar 119, another spring 153 being connected to the cross-bar 148 and also to the upper portion of the finger bar for yieldingly forcing the latter downward. 50 The lower end of the finger bar has a finger 154 that projects rearward, the bar having also a thumb 155 that projects rearward above the finger and is adapted to slide in the guide channel 124. The thumb and finger 55 are adapted to embrace a button for moving it down the curved guide bar 119 to the required position, the thumb being suitably adapted to pass through the slot 140 in the gate that holds the buttons. The 60 guide pin 147 projects beyond the side plate 146 of the open head, and when the finger bar is carried upward for the purpose of withdrawing the button from the gate the guide pin rides upward upon the curved 65 guide 141 and carries the open head suffi- ciently high to prevent the thumb 155 from striking the lowermost button and forcing the buttons upward, the guide pin 147 being carried off of the upper end of the guide 141 and permitted to descend to the guide 142 70 and downward under the guide 141 while the thumb engages the rear side of the button and gently pushes the button down from beneath the gate 139, the thumb entering the aperture 138 behind the button and passing 75 through the slot 140. When the thumb is engaging the button the spring 153 permits the finger bar to yield slightly during the downward movement of the arm 73, so as to avoid shock or straining of the various parts. 80 The spring 152 permits the open head to swing so that the finger bar 149 may follow the contour of the curved guide bar 119, the lower portion of which is straight; the spring also permitting the guide pin 147 when carried over the guide 141 to cause the finger bar to swing upwardly to clear the lowermost one of the buttons and pass over it without thrusting the button backward from the gate 139. The button-attaching mechanism 85 includes a shear block 156 and the main bar 78 co-operates with the shear block to cut off sections of wire to be formed into fastening staples. The shear block has a guide hole 157 therein through which the wire is 90 fed in operation to the face 158 of the guide-way in which the bar 78 is guided. An arm 159 is supported by the head block 21 and supports a holder 160 for the staple wire. A feed lever 161 is supported between its ends 100 on a pivot 162 that is mounted on the housing, and a spring 163 is placed between the wall and the upper portion of the lever for yieldingly forcing the lower end of the lever toward the shear block. The lower portion 105 of the lever has a cam below the pivot and extending into the path of movement of the finger 58, which when drawn downward engages the cam and forces the lever in the opposite or retracting direction. The lower 110 end of the lever has a suitable boxing 165 in which is an eye or hole 166 to receive and guide the staple wire. The lever has a clutch 167 mounted on pin 168. The lever is stopped in its advance movement against 115 a projection 169 having a stud 170 fixedly secured thereto and on which a clutch 171 is mounted and adapted to prevent return of the staple wire. A locking bar 172 is pivotally supported on the stud 170 and has a 120 finger 173 thereon that extends adjacent to the lower end of the guide bar 119 and disposed so as to be engaged by the guide pin 147 and pushed downward when the finger bar 149 is moving a button to the lower end 125 of the guide bar, but permits the guide pin to pass the finger when there is no button engaged by the finger bar, the latter in such case being swung into contact with the guide bar 119. The locking bar 172 has a hori- 130

horizontal slot 174 therein whereby the bar is guided on the guide pin 168 during movement of the lever 161. The locking bar has also a recess 175 extending upward from the slot to receive the guide pin 168 and thereby lock the lever when the latter is retracted, so that feeding of the wire is prevented in case the machine fails to bring a button to the proper position for use. The wire 176 10 is fed through the guide hole 157 to be cut off into sections 177. When the eye or shank 178 of a button 179 is placed on the arbor 91 the section of wire extends through the eye and over the top of the arbor to be formed into a loop to constitute a staple.

The plate 136 that is pivotally mounted upon the frame member 125 has a laterally projecting finger 184 that extends under the guide 142 whereby to manually lift the gate 139 by means of the guide 141 which is conveniently shaped to constitute a finger-piece whereby to directly lift up the plate 136.

In practical use a variety of buttons of different character, as to size and color, 25 are provided and the supply of wire is placed on the holder provided therefor. The two kinds of buttons most commonly desired are placed in the magazine and separated by the partition 37, another kind being placed 30 in the channel 47, and still another kind in the channel 49, still other varieties if required being placed in the receptacles of the table 11. The stops being adjusted to normal position, the fingers 132 extend downward and retain the buttons in the guide channels, the channels 45 and 46 being supplied from the magazine by the elevators 40 and 41 on repeated operation of the foot lever 7. When a selection of buttons is made 35 for use, the stop holding such buttons is retracted and the buttons permitted to slide down the chute to the gate 39 which temporarily holds them until taken away periodically by the finger bar 149, but may all be released and removed by manually lifting 40 the gate in case it is desired to use another variety of buttons. The contours of the different cam portions of the cam plate or bar 55 are such as to hold the arbor bar 90 in projected position and the main bar 78 and the ram 86 in elevated position when the cam plate is elevated, the feed lever 161 at such times forcing the wire into the proper position to be cut off if the lever is unlocked by 50 the pin 147 engaging the finger 173. The article to which the button is to be applied is placed upon the anvil 116, and the eye of the button resting on the arbor having received the section of wire, the cam plate or 55 bar 56 on downward movement causes the main bar 78 to move downward and cut off the wire followed by downward movement of the ram 86 with the main bar, which enables the main bar to bend the section of 60 wire over the top of the arbor while the ram

temporarily rests upon the wire and holds it tightly upon the under portion of the eye of the button while the staple is being formed, after which the arbor is caused to be retracted by the cam plate, the latter by 70 means of the higher cam portions therein causing downward movement of both the main bar 78 and the ram 86 to carry the staple and the button to the work upon the anvil, the motion of the main bar, however, 75 being arrested before coming into contact with the shoe or other article while the ram is forced to descend and drive the staple through the article to clinch the legs on the anvil. While the cam plate 56 is descending, 80 the arm 73 is swung upward to enable the finger bar to engage another button for bringing it down to the required position on upward movement of the cam plate. When the arm 73 is carried upward the arm 85 71 is swung downward to permit the elevators 40 and 41 to descend, the latter being again elevated by the upward movement of the arm 71. When the elevators are lowered the buttons gravitate to the tops thereof and are thereby lifted when the elevators are lifted to permit the buttons to slide downward onto the chute. The whole operation is rapidly caused to be performed by means of the foot lever 7 while the operator 90 handles the work with both hands free for the purpose and with a clear view of the button-attaching operations. The purpose and function of the various elements of the machine having been fully pointed out in 100 connection with the description of the construction thereof, the various motions and results of operation of the various elements will be clearly understood without further description in detail.

It should be understood that various modifications may be made with reference to the details of construction of the machine as may in practice be found desirable within the scope of the appended claims.

Having thus described the invention, what is claimed as new is,—

1. In a button-attaching machine, an inclined chute for movably guiding the buttons, a guide plate fixedly supported above the chute and having a slot therein, and a tumbling stop device pivotally supported upon the guide plate and having a finger to be moved through the slot and into the path of movement of the buttons, the device having also a controlling arm normally engaging the top of the guide plate.

2. In a button-attaching machine, a housing having a table thereon, a magazine fixedly connected to the housing above the table, a chute extending from the top of the magazine, an elevator extending through and vertically movable in the bottom of the magazine and provided with a controlling rod that extends through the table, the rod

130

having two stop devices thereon arranged respectively above and below the table, and means for lifting the elevator to carry buttons from the magazine to the chute.

5 3. In a button-attaching machine, an inclined chute for movably guiding buttons, a guide plate fixedly supported above the chute, a curved guide bar connected to the lower end of the chute, a gate hinged to the 10 top of the guide plate and extending downward over the lower end of the guide plate to the guide bar to hold the buttons, and a lifting device hinged to and normally resting on the top of the guide plate and having 15 a finger extending under a portion of the gate for lifting the gate to release the buttons, the lifting device having a projecting handle portion.

4. In a button-attaching machine, a gravity chute having two guide channels converging each to the other and also a single channel extending from the junction of the convergent channels, the chute having also two straight guide channels extending to 25 the two convergent channels respectively, a magazine frame connected to the chute and having two guide channels that extend to the two convergent channels respectively, a magazine body secured to the magazine 30 frame and having a partition wall therein on a plane between the straight guide channels, and two elevators vertically guided on opposite sides respectively of the partition wall and having channels for carrying the 35 buttons to the two straight channels.

5. In a button-attaching machine, a chute for guiding buttons, a curved guide extending downwardly from the end of the chute and having a guide channel therein, a pivotally supported lever provided on its free end with a pivot, an open head swingingly hung on the pivot and provided below the pivot with a guide pin, a finger bar movably arranged in the head and having two slots 45 therein, one slot receiving the pivot and the other receiving the guide pin for vertically guiding the finger bar, the finger bar having on its lower end a thumb and also a finger projecting below the thumb, the 50 thumb being normally guided in the guide channel, a spring connected to the head and the finger bar for yieldingly forcing the bar downward in the head, and a spring co-operating with the lever and the head for 55 yieldingly forcing the thumb of the finger bar into the guide channel.

6. In a button-attaching machine, the combination with a chute, and a curved guide extending downwardly from the 60 chute, of a pivotally supported arm having a pivot pin on one side thereof extending opposite the front of the curved guide, an open head comprising two separated plates connected to swing on said pin and a guide 65 pin secured to the two plates below said pin,

said plates having a cross-bar secured thereto forward of said pins, an S-shaped finger bar movably arranged between said plates and having a longitudinal slot therein receiving said pivot pin and also a longitudinal slot receiving said guide pin for vertically guiding said finger bar and permitting the bar to swing with said head on said pivot pin, the lower end of said finger bar extending toward said curved guide for engaging buttons on said guide, the upper end of the bar extending away from the guide and above said cross-bar, a spring connected to said upper end and to said cross-bar and yieldingly forcing said finger 70 bar downward in said head, and a spring co-operating with said arm and also with the said head adjacent said guide pin for yieldingly forcing the lower portion of said finger bar to said curved guide. 75

7. In a button-attaching machine, the combination with a housing, of a chute on the top of the housing, a curved guide bar connected to the chute and extending forward and downwardly therefrom, an arm 90 pivotally supported on one side of the housing and having a boss on one side thereof, the boss having a pivot pin extending opposite the front of the guide bar, means for moving and controlling the arm, a head supported to rock on said pivot pin and provided below the pin with a guide pin, a finger bar having two longitudinal guide slots therein, one of the slots receiving the pivot pin, the other slot receiving the guide 95 pin, for vertically guiding the bar and permitting the bar to swing on the pivot pin, a spring co-operating with the boss and the head for yieldingly pressing the lower portion of the finger bar to the curved guide, 100 and a spring connected with the finger bar and the head for yieldingly pressing the finger bar downward relatively to the head. 105

8. In a button-attaching machine, the combination of a base, a hollow pillar on 110 the base, a foot-lever pivoted to the base, a housing fixedly secured upon the pillar and having a series of teeth on the inner side thereof, a cam plate vertically movable in the housing, a rod extending through the 115 pillar and connected to the foot-lever and also to the cam plate, a dog pivoted to the cam plate for engaging said teeth, a guide pin supported by the housing to be engaged by the dog for forcing the dog into engagement with said teeth when said cam plate has been moved upward, and a guide pin supported by said housing to be engaged by 120 said dog for retracting the dog from said teeth when said cam plate has been moved downward, with button-feeding mechanism mounted on said housing and operated and controlled by said cam plate.

9. In a button-attaching machine, the combination of a housing including a back 130

wall having an inclined upper portion extending inward and upward, said portion having a rib on the outer side thereof, an inclined chute on the top of the housing 5 having an open magazine frame on its upper end and also a tongue extending onto said rib, a magazine body secured to said frame and said inclined wall portion, a partition in the magazine connected to said rib 10 and said tongue, two elevators connected together at their lower ends and vertically movable on opposite sides respectively of the partition for lifting buttons from the magazine body to the tongue of said chute, 15 a spring secured to the bottom of said elevators, and a lever pivoted to said housing and having a projection thereon extending under said spring for lifting the elevators.

10. In a button-attaching machine, the 20 combination of an inclined chute having two guide channels in its top converging each to the other and also a single channel connected with the two channels, the chute having two separated inclined frame bars connected thereto that have guide channels leading respectively to the two converging channels, the chute having also an intermediate channel between said two channels and in communication with the single channel, a magazine body secured to said frame bars, and an elevator vertically movable in the magazine and having a top that is inclined to correspond to the plane of said frame bars, said top having a channel to lead to said intermediate channel.

11. In a button-attaching machine, the 40 combination of a housing, a magazine fixedly supported by the housing, a chute on the housing extending from the top of the magazine, a guide bar extending from the chute, an elevator vertically movable in the magazine for lifting buttons from the magazine to the chute, a lever pivotally supported between its ends on the housing and having one 45 arm thereof operatively connected with the elevator for vertically lifting the elevator, and a finger bar carried by the opposite arm of the lever for bringing the buttons down the guide bar from the chute when the 50 elevator is lifting buttons from the magazine.

12. In a button-attaching machine, the 55 combination of a magazine for buttons, a chute having a tongue extending into one side of the magazine, the tongue having two guide channels for the buttons in its top that extend down the chute, a vertical partition in the magazine on a plane between the channels, two elevators movable vertically on opposite sides respectively of the partition and having channeled tops inclined toward said tongue for lifting buttons from the magazine to the channels respectively in said tongue,

and two guides supported above said tongue and extending divergently each from the other and from said partition for deflecting buttons not guided on said tongue over and into said magazine.

13. In a button-attaching machine, the 70 combination with a chute for guiding buttons, of a guide plate supported by the chute at a distance above the top thereof, a gate pivoted upon the guide plate and extending downward beyond the end of the plate toward the chute and having a guide on one side thereof, the gate being adapted to hold the buttons on the chute, and a lifting device pivoted upon the guide plate adjacent to the gate and having a finger thereon extending under said guide to engage the guide for 75 lifting the gate to release the buttons, said device having a finger-piece thereon for lifting the device.

14. In a button-attaching machine, the 80 combination of an inclined chute having two guide channels therein converging each toward the other and also two parallel channels extending to the ends of the convergent channels respectively, and a guide bar connected to the lower end of the chute and having two channel sections therein converging each to the other and connected respectively with the two convergent channels and the parallel channels, the guide bar having also a single channel therein extending from the 85 junction of the two channel sections.

15. In a button-attaching machine, the 90 combination of a magazine, a vertical partition in the magazine extending beyond the top thereof, two elevator devices coupled together at their lower ends and movable vertically on opposite sides respectively of the partition and through the bottom of the magazine, a chute extending from the plane of the top of the magazine, means for lifting 95 the elevator devices, and means for stopping the upward movement of the elevator devices with their tops on the plane of the chute and below the plane of the top of said partition.

16. In a button-attaching machine, the 100 combination of an inclined chute having an open frame thereon, a magazine body secured to the frame, an elevator vertically movable in the magazine body and into said frame for lifting buttons from said body onto said chute, a lid frame supported upon said open frame, and a lid hinged to said lid frame.

In testimony whereof, I affix my signature 110 in presence of two witnesses.

ALBERT E. TOLIN.
